PENCIL OR SIMILAR ARTICLE

Meyer M. Brown, New York, N. Y.

Application April 19, 1950, Serial No. 9,337

Term of patent 7 years

(Cl. D74—24)

To all whom it may concern:

Be it known that I, Meyer M. Brown, a citizen of the United States of America, residing in the county, city, and State of New York, have invented a new, original, and ornamental Design for a Pencil or Similar Article, of which the following is a specification, reference being had to the accompanying drawing, forming a part thereof.

In the drawing:

Fig. 1 is an elevational view of a pencil or similar article showing the essential feature of my new design in full lines.

Fig. 2 is a cross-sectional view taken on line 2—2 of Fig. 1.

I claim:

The ornamental design for a pencil or similar article, as shown and described.

MEYER M. BROWN.
